UNITED STATES PATENT OFFICE.

B JEAN RALEIGH, OF WASHINGTON, DISTRICT OF COLUMBIA.

BELT BUCKLE.

Application filed June 8, 1922. Serial No. 566,788.

To all whom it may concern:

Be it known that I, B JEAN RALEIGH, a citizen of the United States, residing at Washington, District of Columbia, have 5 invented certain new and useful Improvements in Belt Buckles, of which the following is a specification.

This invention relates to improvements in belt buckles and more particularly to belt 10 buckles that are adjustable to any size and are adapted to frictionally engage the belt as distinguished from that type provided with a pin passing through a belt hole.

One of the objects of the present invention 15 is to provide a simple and practical belt buckle of the above character having relatively few parts which may be inexpensively manufactured and assembled.

A further object is to provide a belt 20 buckle of the above character which will not mar or mutilate the belt in any way and will co-act with the belt of any reasonable desired thickness or thinness, and, furthermore, will positively prevent slipping of the 25 belt regardless of variations in thickness.

With these and other objects in mind, as will appear obvious from the following description, attention is directed to the accompanying drawings illustrating three of various 30 possible embodiments of the invention all operating upon substantially the same principle.

In these drawings, wherein similar reference characters denote corresponding parts— 35

Fig. 1 is a longitudinal, partial sectional view of one form of belt buckle;

Fig. 2 is a similar view of a modified form of buckle;

Fig. 3 is a similar view showing a still 40 further modification.

Referring to the drawings in detail and more particularly to Figure 1, 5 denotes the body portion of the belt buckle which is of channel shape in cross section, that is, 45 provided with upper and lower parts 6 and 7 respectively. Near one end is mounted an L-shaped belt engaging member 8 pivoted at 10, one portion 11 of which is adapted to coact with one end of the belt 12, while 50 the other end of the belt 13 passes through the channel shaped portions of the buckle and is gripped between the belt engaging portion 14 of one member and a lug or thickened portion 15 on the other. In the 55 form shown in Figure 1, the part 14 swings about the center 10 on an arc, as indicated

by the letter R, while the lug or projection 15 has a curved portion between the parts *a* and *b*, which is struck from a slightly gradual radius and from a center eccentric to the point 10. It will thus be seen that as the member 14 swings relatively towards the right it will gradually approach the portion 15 adjacent the letter *b*, thus gripping the belt between the parts 14 and 15 regardless of its thickness.

In the modification shown in Figure 2, the parts between the letters *a* and *b* is substantially straight instead of being struck on a curve and the part 14 is provided with two gripping teeth 17 and 18, one being slightly longer than the other thereby to more effectively engage the belt. The modification shown in Figure 3 is substantially the same as that above described except that the thickened part preferably extends substantially the entire length of the buckle as at 15^a.

In all of these modifications the primary thought will be self-evident, that is, as tension is exerted upon the belt the member 14 will be drawn over towards the part 15 regardless of the thickness of the belt, thereby to urge a constantly increasing gripping action upon the belt and positively prevent its slipping. Furthermore, there will be no marks or mutilations left upon the belt as the pressure is so evenly distributed and gradually applied.

It will thus be seen that the present invention provides a simple and practical belt buckle and one that will be efficient and practical in operation, and while I have described my invention in connection with certain preferred embodiments, I wish it understood that I do not limit my invention to the embodiments shown and described, except in so far as specific limitations may appear in the appended claims.

I claim:

1. A belt buckle comprising a plate member and a clamping element adapted to frictionally grip a belt therebetween, said plate member having depending side flanges, said clamping element being pivotally mounted in said flanges, said plate member having on its underface an inclined wedging portion, one belt extremity being joined to said clamping element, the clamping element being adapted to swing towards and continue to approach said inclined wedging portion as tension is exerted on the belt,

thereby to more tightly grip the other end of the belt therebetween.

2. A belt buckle comprising a plate member and a clamping element adapted to frictionally hold a belt therebetween, said clamping element being pivotally mounted on said plate member, said plate member being thickened on its underface to provide a curved surface, said clamping element adapted to gradually approach said curved surface in an arc which intersects the line of curvature of said curved surface at a slight distance beyond the termination of said curved surface, whereby a progressive wedging action is provided to more tightly grip the belt.

3. A belt buckle comprising a face member having vertically and longitudinally extending flanges, a clamping member pivotally mounted in said flanges, said plate member being thickened to provide a curved surface on its underface, said clamping

member, when swung about its pivot point, being adapted to gradually approach said curved surface as tension is exerted, thereby 25 to more tightly grip the belt therebetween, the radius of the curved surface and the clamping member being of different lengths and from different centers.

4. In a belt buckle, in combination, a face 30 member, having vertically and longitudinally extending flanges, an L-shaped member pivotally mounted in said flanges, said face member having on its inside face a thickened portion, said L-shaped member 35 adapted to swing about its axis in a direction opposite to the tensile force exerted by the belt and in an arc which gradually approaches and continues to approach said thickened section to form friction holding 40 means for the belt.

In testimony whereof I affix my signature.

B JEAN RALEIGH.
